CLAIM

The ornamental design for a speedometer/odometer, as shown.

DESCRIPTION

FIG. 1 is a right front perspective view of a speedometer/odometer showing my new design;
FIG. 2 is a right side elevational view thereof, the left side being a mirror image thereto;
FIG. 3 is a front elevational view thereof;
FIG. 4 is a top plan view thereof;
FIG. 5 is a right front perspective view of another embodiment of my new design of FIGS. 1-4;
FIG. 6 is a right side elevational view thereof, the left side being a mirror image thereto;
FIG. 7 is a front elevational view thereof;
FIG. 8 is a bottom plan view thereof.
